UNITED STATES PATENT OFFICE.

GILBERT E. FERRY, OF OMAHA, NEBRASKA.

SHOCK ABSORBER FOR SCREEN DOORS.

Application filed April 11, 1921. Serial No. 460,388.

To all whom it may concern:

Be it known that I, GILBERT E. FERRY, a citizen of the United States, residing at Omaha, in the county of Douglas and State 5 of Nebraska, have invented certain new and useful Improvements in Shock Absorbers for Screen Doors, of which the following is a specification.

This invention relates to a device for use 10 in connection with screen doors to prevent undue shocks occasioned by the door when swinging under force of its spring to a closed position, and has for its object to provide means for this purpose consisting 15 of few and simple parts so that it may be economically manufactured, will be durable in wear and will be effective in use to prevent jars or excessive vibration.

With the foregoing objects in view the invention presents a novel construction, combination and arrangement of parts, as described herein and claimed, and as illustrated in the accompanying drawing, wherein,—

Fig. 1 is a side view, partly in section, showing the device secured to a part of a door frame, the buffer-bar being disposed in its normal, horizontal position. Fig. 2 is a sectional view on line 2—2 of Fig. 1. 25 Fig. 3 is a view of similar parts shown in Fig. 1, a part of a screen door, in section, being added, and the buffer-bar being shown in an inclined position. Fig. 4 is a broken away view showing a screen door and door 30 frame. Figs. 5 and 6 illustrate a modified form of the invention showing, respectively, the buffer bar in horizontal and inclined positions.

Referring now to the drawing, the invention is shown and described in connection 40 with a screen door 7, mounted by means of hinges 8, to swing from a part of the door frame, and provided with a spring 9; and it will be understood that when the screen 45 door is opened, it will normally move to a closed position, the vertical strip *a* of the door moving into engagement with the upright strip *b* of the door frame by action 50 of the spring 9, the contact of these parts being attended with considerable vibration and objectionable noise, depending upon the force exerted by the spring.

To prevent the objectionable shocks and noise mentioned, I provide any suitable support, shown herein as a casing 10, to be disposed close to the edge of the strip *b* of the

door frame and secured thereto by screws or other suitable keepers 11, said casing having an opening *c* in one of its ends between its side walls.

In the embodiment of the invention shown in Figs. 1, 2 and 3, numeral 12 indicates an elongated, resilient body or buffer-bar provided near its inner end with a staple or equivalent holder 13, and supported in a horizontal position by any suitable means, the means herein shown being the lower pair of members 11, said bar 12 being normally disposed with one of its ends extending outwardly of the plane of the upright strip *b* 60 of the door frame, and normally maintained in said extended position by means of a spring 14 having one of its ends connected with the holder 13, its opposite end being mounted upon a stationary pivot-member 65 or pin 15 at the outer end of the casing.

On account of the construction described, the inner end of the bar 12 will normally be disposed adjacent to a stop-member, the stop-member herein shown being the stationary wall *d* of the casing 10, and in operation, when the screen door swings toward the upright strip *b* of the door frame for a closed relation therewith, it will strike the resilient bar 12 with considerable force and 70 will move it against the stop-member or wall *d* against the force of the spring 14, which will cause the screen door to rebound a short distance. As soon as the door rebounds the spring 14 will cause the bar 12 75 to again move outwardly of the casing. The second swinging movement of the screen door toward the door frame will be 80 accompanied with lesser force than its first movement and this force will be so slight 85 that the bar 12 will strike the stop-member *d* lightly, and will cause the door to rebound only an appreciable distance. The door then, by action of the spring 9 will be urged 90 to a closed position, its force being so slight 95 that the spring 14 will not be extended, the result being that the inner end of the bar 12 will move upwardly to the position shown in Fig. 3, the spring 14 being retracted and causing the movement of the bar to be limited to a circle's arc and operating to maintain the staple 13 equidistant from the pin 15 at all times except when the bar 12, while disposed horizontally, is moved against the stop-member or wall *d*.

The device does not operate at any time to prevent or hinder a complete closure of

the screen door. While the door remains closed the bar 12 will remain in an inclined position, as shown in Fig. 3, and when the door is opened the bar 12 will move by action of gravity to a horizontal position with its outer end projecting outwardly of the casing and outwardly of the door frame as shown in Fig. 1.

The bar 12 is preferably constructed of 10 india rubber so that all appreciable noise may be avoided when struck by the door. If not constructed of india rubber it should be provided with a tip α , shown in Fig. 6, of india rubber or soft material so that, approximately, no noise will be occasioned when the door strikes the end of the bar. However, I do not wish to limit myself to any particular material in the construction of the buffer-bar.

20 In the modified form shown in Figs. 5 and 6, a stationary, resilient block d' is substituted for the wall d , above described, and the bar 12' is provided with a slot 16 which receives a stationary guide 17, and a weight 25 is shown mounted upon the inner end of the bar 12' which normally causes said bar to move by gravity to a horizontal position when the screen door is opened, the casing 10' and spring 14' remaining the same as 30 already described, the result in the action of the springs 14 and 14', and movements of the buffer-bars 12 and 12' being the same as already described and preventing undue shocks and vibration.

35 It will be seen that operation would be the same if the casing was dispensed with, provided of course, that equivalent, stationary pins 15 or 15' and stop-members d or d' were provided for the device, and I do 40 not wish to be limited to the use of a casing, but said casing is preferred since the buffer-bars will be protected from injury or displacement.

It will be appreciated that the device may 45 be manufactured at a very limited cost since the parts are few, and that any person of ordinary skill may readily apply the device to a door frame in operative position.

It will be seen that the operation of the 50 device requires that the buffer-bar should be

disposed in, approximately, a horizontal position when the screen door strikes it with considerable force so that the force of the blow delivered by the door will be sustained by the resilient bar and spring, for preventing excessive vibration and noise. Also further operation requires that the buffer-bar shall be moved or pressed outwardly of the casing by the spring 14 for re-engagement with the door, so that secondary and 60 lesser shocks may be absorbed, and that the bar may be swung upwardly in the casing to permit the door to be disposed in closed relation with the door frame, this upward 65 swinging movement being caused, in part, by pressure of the door upon the outer end of the bar and, in part, by the spring 14 which, while retracted, prevents a horizontal movement of the bar and causes it to move 70 in a circle's arc.

I claim as my invention, —

1. In a shock absorbing device, a stationary support including a stop-member, a buffer-bar normally disposed in approximately a horizontal position with its inner end adjacent to the stop-member and with its outer end projecting outwardly of the plane of the support, and a spring connected with the support and said bar for normally resisting a horizontal movement of 80 the bar and for causing a swinging movement of the bar when moved to dispose its outer end in the plane of said support.

2. In a shock absorbing device, a casing 85 having a stop-member, a buffer-bar within and having an end-portion normally projecting outwardly of the casing, means to normally support the bar in a horizontal position, and means engaging the casing and said bar for resisting a horizontal movement of the bar, and for causing the bar to swing to an inclined position when moved 90 inwardly of the casing.

In testimony whereof, I have affixed my signature in presence of two witnesses.

GILBERT E. FERRY.
